J. H. WEBER

MEDICINAL ROLLER

Filed May 14, 1925

Patented Mar. 27, 1928.

1,664,009

UNITED STATES PATENT OFFICE.

JACOB H. WEBER, OF BROOKLYN, NEW YORK.

MEDICINAL ROLLER.

Application filed May 14, 1925. Serial No. 30,189.

This invention relates to medical appliances and particularly to a type thereof which may be advantageously utilized by patients themselves.

5 The medicinal effects of hot salt air, when applied to the skin of a patient suffering from various diseases, such as neuritis, rheumatism, sciatica, gout, etc., are commonly acknowledged, but the treatment with such 10 hot salt air has been impossible for the average person without the services of a skilled attendant.

An object of this invention is to provide an improved medical appliance by means of 15 which anyone may easily and readily obtain all the advantages of the hot salt air treatment for various diseases; which may be readily and easily manipulated by either the patient or another; which will be safe and 20 convenient to use, effective in results, and relatively simple, practical and inexpensive.

Various other objects and features will be apparent from the following description of 25 two embodiments of the invention, and the novel features will be particularly pointed out in connection with the appended claims.

In the accompanying drawing:

Fig. 1 is a side elevation of a medical appliance constructed in accordance with the 30 invention;

Fig. 2 is a sectional plan of the same, the section being taken substantially along the line 2—2 of Fig. 1;

Fig. 3 is an end elevation of the same.

35 In the embodiment of the invention illustrated in the drawing a somewhat cylindrical shell 1 of suitable material, such as thin metal, is provided at one end with a base 2 and at the other end with a removable closure 3, the latter being locked upon the shell in any suitable manner, such as by friction, or by means of a pin 4 which cooperates with a bayonet slot 5 in the adjacent end of the shell. Among the materials which have 40 been found advantageous for the shell, is thin sheet aluminum, and the periphery of the same is reticulated, that is, provided with a large number of small apertures *a* for a purpose which will appear shortly.

50 The base 2 and cap 3 are provided with bearing pins or extensions 6 and 7 respectively, which are rotatably mounted in the fork arms 8 and 9 of a handle 10, the pins 6 and 7 projecting axially of the shell, so 55 that the shell may be rolled over a surface by suitable manipulation of the handle 10.

Within the shell, a suitable heating unit or device 11 is disposed in spaced relation to the walls of the shell, and in the form illustrated, is in the nature of an electric lamp or bulb having a filament which is heated by the passage of an electric current therethrough. The lamp 11 is mounted in a suitable socket 12 which is carried by the shell base 2, so as to project into the interior of 60 the shell.

65 The handle 10 and the arms 8 and 9 may be, and preferably are, formed of insulating material, and the arms 8 and 9 thereof carry spring contacts 13, which are adapted to 70 press upon the ends of the pins 6 and 7. Conductors 14 lead from the contacts 13 and thence as part of a cable 15 to a suitable source of electric current (not shown). The pin 6, which is co-axial with the base or socket 75 12, may be insulated from the socket shell and electrically connected to one of the socket terminals, so that current from one of the conductors 14 may pass through one of the spring contacts 13 to the pin 6, and 80 thence to one of the socket terminals engaged by the lamp base.

85 The other terminal of the lamp socket may be grounded to the base 2 and the shell, and thence through the pin 7 a circuit is completed to the other spring contact 13 and the other conductor 14. The operating current may be conducted to the lamp or the heating unit in any suitable manner, but the construction described for this purpose 90 is relatively simple, and has been found to be satisfactory when relatively low voltage currents are used for the lighting of the lamp.

95 The shell is rotatably mounted between the fork arms 8 and 9 of the handle in such a manner that it may be readily and easily removed therefrom when it is to be filled with crystal or granular salt or other medicinal substance. To permit of such removal in a simple manner, the arms of the handle may have slots 16 extending outwardly from the bearing apertures for the pins 6 and 7, which slots are closed by similarly shaped blocks 17, carried by clasp 100 or latch elements 18. The elements 18 are pivoted to the arms 8 and 9, as at 19, so that the blocks 17 may be swung into and out of the slots 16.

105 When the elements 18 are swung into positions to close the slots 16, as shown in full lines in Fig. 3, the pins 6 and 7 will be locked.

within the fork arms and when the latch elements 18 are swung into the positions shown in dot and dash lines in Fig. 3, the blocks 17 will be carried out of the slots 16, 5 so as to permit removal of the shell from the fork arms. The latch elements 18 have resilient hook shaped ends 20 which are adapted to snap or spring over the convex ends of the arms 8 and 9, so as to yieldingly lock 10 the elements in the full line positions for confining the shell to the handle.

The shell is preferably provided with transverse corrugations 22, that is, made undulating from end to end, so that when 15 rolled over the irregular surface of a patient's body, some of the corrugations will enter the cavities or depressions in the body of the patient and insure action of the medicinal substance thereon.

20 The shell is to be filled with a medicinal substance 21, such as crystal or granular salt, which surrounds the lamp or heating unit 11 and which will be heated thereby while the shell is being rotated. The medicinal 25 substance may be inserted in the shell by first removing the shell from the handle and then removing the closure 3.

In simpler forms of the appliance, the electric unit may be omitted, and the shell 30 mounted in the manner shown in the drawings with the contacts 13 and conductors 14 omitted. The shell is filled with hot crystal or granular salt or other medicinal substance, mounted in the handle, and manipulated over the patient's body until the medicinal substance has cooled, whereupon the shell may be removed, the medicinal substance reheated and returned, whereupon the shell may be replaced and the treatment 40 continued.

In the embodiment of the invention as illustrated, it will be observed that a thin shell having a reticulated or apertured wall and containing a hot medicinal substance, 45 such as crystal or granular salt, may be rolled over the portion of a patient's body to be treated, and the hot salt air, which emerges from the apertures of the shell wall and contacts with the skin of the patient's 50 body, will have a medicinal and beneficial effect thereon. This hot salt air, for example, has the effect of reducing inflammation and relieving pain and congestion in cases of neuritis, rheumatism and various other diseases. In fact, a patient suffering from 55 such diseases is very much relieved by treatments with such an appliance, and shows great improvement with repeated use of the appliance. In the illustrated embodiment the medicinal substance may be kept hot while being used, whereas in a simpler form without the heating unit, it will be necessary at intervals to remove the medicinal substance, heat it, and return it to the shell.

60 By reason of the undulations or corruga-

tions in the shell periphery, the shell may be caused to reach all surface portions of the flesh being treated. For example, such corrugations are particularly valuable when the roller is being passed along the spine of 70 the patient, in which case the corrugations enter the normal depressions in the flesh and thus insure the action of the medicinal substance upon all of the patient's body being treated.

75

It will be obvious that the shell with reticulated periphery, when filled with a medicinal substance such as hot salt, may be rolled over the patient's skin without the use of a handle by merely rolling the roller with 80 one's hand in a well known simple manner. Obviously the use of the handle is preferable especially where a hot substance is employed in the shell.

It will be understood that various changes 85 in the details, which have been herein described and illustrated for the purpose of explaining the nature of the invention, may be made by those skilled in the art within the principle and scope of the invention, as 90 expressed in the appended claims.

I claim:

1. A therapeutic device comprising a handle having apertured forked arms, slots in said arms leading to said apertures, and a 95 hollow perforated roller mounted within said arms including a base member, a cap, pins carried by said base and cap, an electric heating element extending into said roller supported by said base, contacts 100 mounted on said arms contacting with said pins and electrical connections between said pins and said heating element.

2. A therapeutic device comprising a handle having apertured forked arms, slots in 105 said arms leading to said apertures, closures for said slots, a hollow perforated roller mounted within said arms including a base member and cap, pins carried by said base and cap, an electric heating element 110 extending into said roller supported by said base, contacts mounted on said arms contacting with said pins and electrical connections between said pins and said heating element.

3. A therapeutic device comprising a handle having apertured forked arms, slots in said arms leading to said apertures, closures for said slots pivotally mounted in said arms, a hollow perforated roller mounted 120 within said arms including a base member and cap, pins carried by said base and cap, an electric heating element extending into said roller supported by said base, contacts mounted on said arms contacting with said 125 pins and electrical connections between said pins and said heating element.

In witness whereof, I hereunto subscribe my signature.

JACOB H. WEBER.
